(57) **CLAIM**

The ornamental design for a biological fluid collection device, as shown.

DESCRIPTION

FIG. 1 is a perspective view of a biological fluid collection device showing our new design;

FIG. 2 is an elevation end-view thereof;

FIG. 3 is a first side-elevation view thereof; and,

FIG. 4 is a second side-elevation thereof.

The portion of the biological fluid collection device depicted in broken lines forms no part of the claimed design. A side-elevation view opposite the first side-elevation view is omitted as such would be identical to the first side-elevation view. Likewise, a side-elevation view opposite the second side-elevation view is omitted as such would be identical to the second side-elevation view.
